HIS ATTORNEY.

UNITED STATES PATENT OFFICE.

HUGO LENTZ, OF BERLIN, GERMANY.

NOZZLE FOR TURBINE-ENGINES.

No. 813,806.

Specification of Letters Patent.

Patented Feb. 27, 1906.

Original application filed April 4, 1905, Serial No. 253,753. Divided and this application filed October 17, 1905. Serial No. 283,091.

To all whom it may concern:

Be it known that I, HUGO LENTZ, a subject of the German Emperor, residing at 10-11 Potsdamerstrasse, Berlin, Germany, have 5 invented new and useful Improvements in Nozzles for Turbine-Engines; and I do hereby declare the following to be a full, clear, and exact description of the same.

The object of this invention is the production of a novel form of supply-nozzle for steam or gas turbines and which results in economy of maintenance and in increased power of the wheel to which the nozzle delivers the pressure medium.

15 This application is a division of an application filed by me April 4, 1905, Serial No. 253,753, for Letters Patent of the United States.

It has been observed that at the outflow of 20 elastic liquid from a simple though well-rounded mouth into the open atmosphere a certain outflow speed corresponding to the velocity of sound is never exceeded. However, in order to commute the steam energy 25 in as complete a manner as possible into kinetic energy and to produce therewith mechanical working effect in a turbine De Laval has constructed a nozzle with a conical enlargement wherein the steam expands 30 until the steam compression is attained and its particles hastened in the measure of the transformed energy of heat. The various forms of such conical nozzles comprise, so far as I am aware, chambers closed on all sides 35 and which continuously surround the expanding jet of liquid which is being delivered.

Theoretical considerations of turbines teach that as tangential an impact as possible is to be aimed at, although the conditions 40 of construction usually make the selection of a proportionately larger angle of impact unnecessary. The nearer the theoretic conditions are approached the thinner will be the nozzle-walls until the attainable limit is 45 reached. The production of such thin walls results in a nozzle-wall tapering to and terminating in a wedge-shape point which is not only difficult to produce, but readily breaks and causes difficulties, especially at 50 the sharp outer edges.

I have devised a new and simple form of nozzle which does not have the defects mentioned and by which I realize more closely than heretofore the theoretically-desirable 55 conditions. The new nozzle is so arranged

with respect to the turbine-wheel that the paddles of such wheel partially constitute the walls of the nozzle. Obviously such new features of construction may also be embodied in the steam races or channels which 60 re-present the steam to the same wheel or which project it against the paddles of another wheel.

Figures 1, 2, and 3 of the accompanying drawings show somewhat diagrammatically one form of such invention.

a indicates the nozzle, which may be of any form desired. One wall or side of the nozzle is much shorter than the opposite wall, and the paddles of the running-wheel constitute, 70 in effect, a continuation of such shorter wall or side, and the steam is as a consequence more directly and positively driven against the paddles than in the case of nozzles all whose sides or walls were of corresponding 75 length. The longer wall or extremity of the nozzle is shown at *d* in the accompanying drawings.

Fig. 1 is a bottom view of the preferred 80 form of new supply-nozzle. Fig. 2 is a sectional view thereof, illustrating the angle at which the pressure medium is delivered and Fig. 3 is a detail view at the dotted line of Figs. 1 and 2 and also showing the relation of the parts.

It will be seen that the nozzle *a* has one long forward overhanging end *d*, which extends alongside of several of the paddles *c* of the running-wheel *b* and also has a very short rear end which may be said to constitute the 90 beginning of the nozzle. The further provision of the side walls of the nozzle converts the same into an inverted shell-like nozzle adapted to deliver the pressure medium directly against the impact-faces of the paddles, 95 which paddles, in effect, constitute a continuation of the short rear end of the nozzle and are the part of the nozzle wherein the expansion of the steam takes place. It will further be observed that my new nozzle is not 100 thinned throughout its length or otherwise weakened and that the delivery extremities of my new nozzle are as thick and as strong as any other parts thereof.

The form of nozzle here under consideration is easy to produce, is durable, and is without defects in operation, owing to the breakage or other cause. It also permits the employment of acute impact angles not heretofore to be considered, owing to the diffi- 110

culties encountered in producing prior forms of nozzles. The selection of the acute angles also permits when the new form of nozzle is used the employment of a form of paddles 5 upon the turbine-wheel having broad faces, as shown in Fig. 9, without losses in impulse and consequent decrease in efficiency.

It will be understood, of course, that my invention may be embodied in nozzles of any 10 kind used with turbine running-wheels, including reverse-guiding or re-presenting devices.

- Having described my invention, what I claim and desire to secure is—
- 15 1. In a turbine-engine, a turbine running-wheel provided with paddles, and a nozzle for delivering pressure medium thereto, said nozzle consisting of successive narrowing and broadening parts, one wall of the broadening 20 part having an opening which runs back to the point of connection of the narrowing and

broadening parts, and which opening is closed by the paddles of the running-wheel.

2. In a turbine-engine, a turbine running-wheel provided with paddles, and a nozzle 25 for delivering pressure medium thereto, said nozzle consisting of successive narrowing and broadening parts, the said broadening part having top and side walls running forward from the point of connection of the narrowing and broadening parts, the bottom wall 30 being entirely cut away forwardly from said point of connection, the opening thus formed being closed by the paddles of the running-wheel.

In testimony whereof I have signed my name to this specification in the presence of two subscribing witnesses.

HUGO LENTZ.
